UNITED STATES PATENT OFFICE

HARRY BONAT, OF NEW YORK, N. Y.

HEATER

Application filed June 27, 1929. Serial No. 373,981.

This invention relates to heaters and more particularly to heaters for use in connection with the permanent waving of hair.

An object of this invention is to provide a new, useful, efficient and inexpensive heater for use in connection with the permanent waving of hair.

The heater of the present invention is composed of two similarly shaped sections each formed as a portion of a cylinder so that when in closed position the completed assembly forms in its interior an almost complete cylinder. The two sections are joined together near the top in such a manner that they are capable of movement one toward the other or away from the other in a lateral direction. Resilient means is provided for normally holding the sections apart from each other and locking means is provided for holding the sections in locked position around the hair to be treated which, as is customary in practice, is wound upon a cylindrical spool.

Other objects and features of the invention will become apparent by reference to the following detailed description considered in connection with the accompanying drawings wherein

Figure 1 is a perspective view of a device embodying the invention illustrated in closed and locked position.

Figure 2 is a plan view of the device.

Figure 3 is an end view of the same device.

Figure 4 is a plan view partially in section of the same device in open position; and

Figure 5 is a section taken on the lines 5-5 of Fig. 2.

Referring now to the drawings, it will be seen that the heater embodying the invention is composed of two similarly shaped sections 10 and 11 joined together near the top thereof. Section 10 is composed of an inner sheet of material indicated at 12 formed in such a manner as to provide a base 13 with an upturned shoulder 14, an arcuate 15 shaped interior 16, a section 17, parallel with the base 13 which has an angular extension 18 and a top portion 19 parallel with the portion 16. Joined to the sheet of material 12 is an outside member 19 of a shape corresponding to the arcuate portion 15 which

outside plate 19 is held in position by means of the overturned members 20 formed as a part of the material 12. Section 11 is made up of a corresponding portion 21 composed of base 22 with upstanding flange 23; arcuate 24, portion 25, parallel with base 22, angular extension 26 and top portion 27. The end of this top portion 27 is provided with an upturned overlapping member 28 which when the device is in closed position 60 overlaps the top 18 to prevent escape of heat from the interior of the device. A plate 29 arcuate shaped and similar to plate 19 is provided for this section.

The angular portions 17 of section 10 and 26 of section 11 are provided at each end with extensions of reduced size 30 and 31 respectively. As will be seen by reference to Fig. 1, each of these extensions 30 and 31 are folded to lie flat against each other and are provided at their extremities with extensions bent to form collars 32 and 33 respectively, each enclosing or surrounding the other extension. By this arrangement at each end of the device it is possible to move 75 the sections 10 and 11 away from each other in a lateral direction or to move them together with the member 28 overlapping the top 18.

The usual heating elements of any type 80 desired (not illustrated herein) may be mounted within the casing of each section which is formed by the arcuate shaped portions 15 and 19 of section 10 and 24 and 29 of section 11, and the electrical conductors 85 for the same may be introduced into the casing in any desired manner, in this instance being shown as passing through handles 35 and 36 secured to the respective sections. These handles are preferably made of some 90 heat insulating material such as bakelite, hard rubber, etc.

For causing the sections to assume normally a spaced relation one relative to the other, a spring member 37 formed of leaves is 95 mounted in the top portion of the device with the extremities of the leaves bearing against the upstanding portions 17 and 26. In order that the sections may be locked in 100 closed position a spring member 38 is se-

cured as illustrated in Fig. 5 to the upstanding part 17 and extends through openings in the materials 12 and 21 through the plate 29 and handle 36 so that it extends beyond the 5 surface of the handle when the device is in closed position. This spring member 38 is provided with an opening 39 which is engaged by a depending extension 40 formed as a part of the material composing the ele- 10 ment 21. This extension 40 is formed by punching a part of the top piece 25 so that it extends downwardly through the normal plane of this portion. Vents 41 are provided in the top members 18 and 27 for the es- 15 cape of surplus steam.

From the foregoing it will be evident that the operation of the device is substantially as follows: Assume that the sections are in expanded or outermost position relative to each 20 other. In this position they are held from further outward movement by engagement of the collars 32 with the collars 33. When it is desired to place the heater in position to supply heat to hair wound upon the usual 25 spool, the device is first positioned over the spool and then the sections moved laterally one towards the other. When they reach their innermost position they are locked in 30 this position by engagement of extension or tab 40 with the opening 39 in the spring 38 since the normal movement of this spring is upward. After the desired amount of heat 35 has been applied to the hair, the heater may be removed by depressing spring 38 (the end of which extends beyond the surface of handle 36) thereby disengaging the tab 40 from opening 39 and permitting the spring 37 to force the sections apart.

It will be evident from the foregoing that 40 the heater of the present invention is one which is simple and inexpensive to manufacture which may be readily applied to or removed from hair wrapped around a spool and which is otherwise efficient in operation. 45 It is to be understood that the invention is not to be limited to the illustrated embodiment but is to be limited only by the scope of the following claims.

I claim:

- 50 1. A heating device of the character described comprising a pair of arcuate shaped heater sections connected together for uniform rectilinear movement.
- 55 2. A heating device of the character described comprising a pair of arcuate shaped heater members, means connecting said members together at the tops thereof for uniform rectilinear movement toward and away from each other.
- 60 3. A heating device of the character described comprising a pair of arcuate shaped heater sections, means connecting said sections together at the tops thereof for uniform rectilinear movement and resilient means for forcing said sections apart.

4. A heating device of the character described comprising a pair of arcuate shaped heater sections, means connecting said sections for slidable rectilinear movement, and means for automatically locking said sections together when they are moved to their limits of approach.

In testimony thereof, I have signed my name to this specification.
